UNITED STATES PATENT OFFICE.

WILLIAM W. DEAN, OF CHICAGO, ILLINOIS, ASSIGNOR, BY MESNE ASSIGNMENTS, TO
BENJAMIN ELECTRIC MANUFACTURING COMPANY, OF CHICAGO, ILLINOIS, A COR-
PORATION OF ILLINOIS.

ELECTRIC-LIGHTING FIXTURE.

1,157,765.

Specification of Letters Patent.

Patented Oct. 26, 1915.

Application filed July 18, 1913. Serial No. 779,728.

To all whom it may concern:

Be it known that I, WILLIAM W. DEAN, a citizen of the United States, residing at Chicago, in the county of Cook and State 5 of Illinois, have invented new and useful Improvements in Electric-Lighting Fixtures, of which the following is a full, clear, concise, and exact description, reference being had to the accompanying drawing, 10 forming a part of this specification.

The present invention relates to electric lighting fixtures, and more particularly to fixtures for lamps employed to illuminate indicating and like instruments.

15 The invention is especially adapted for use with speedometer lamps of automobiles and is disclosed in that connection in this application.

One object of the invention is to provide 20 a fixture which may be readily applied to speedometer or other similar instruments.

Another object is to provide a lamp with a combined reflector and guard which will direct the light rays upon the dial of the 25 instrument and at the same time protect the lamp against breakage.

Another object is to construct the fixture so that it may be readily adjusted to vary the position of the lamp relative to the 30 associated instrument.

Another object is to so arrange the reflector and guard that the lamp may not be removed without first removing the reflector, thereby preventing disconnection or 35 removal of the lamp by meddlers.

Other objects are to produce a fixture having few and simple parts, which may be cheaply manufactured and readily assembled, while maintaining high operating efficiency of the device as a whole, and which 40 may be applied without structural changes to instruments of varying sizes.

The character of the invention will be more fully understood upon reference to the 45 following detailed description taken in connection with the accompanying drawing, and the scope of the invention will be particularly pointed out in the appended claims.

In the drawing Figure 1 is a general perspective view of a portion of an automobile equipped with a fixture constructed in accordance with the present invention and employed in supporting the speedometer lamp; Fig. 2 is a side elevation of the fixture

and speedometer on which it is located; Fig. 3 is a front elevation of the same; Fig. 4 is a separated view of the lamp and fixture parts; Fig. 5 is a top view of the fixture, the clamping rings being broken away; Fig. 6 is a partial sectional view of the same, the plane of section being indicated by the line 9—9 of Fig. 5; Fig. 7 is a partial vertical section of the lamp and associated socket; Fig. 8 is a similar view illustrating the bayonet joint connection between the lamp and socket, and the lamp partially withdrawn; Fig. 9 is a transverse vertical section of the socket and end elevation of the included lamp, the section being taken on a plane indicated by the line 9—9 of Fig. 11; Fig. 10 is a similar section viewed in the opposite direction, the section being taken on a plane indicated by the line 10—10 of Fig. 7; Fig. 11 is an elevation of the lamp and associated socket; and Fig. 12 is a detail section 75 taken on a plane indicated by the line 13—13 of Fig. 10.

Throughout these views like characters refer to like parts.

In the drawing, A designates the fixture 80 which is constructed in accordance with the present invention. It is shown mounted upon a speedometer B whose bracket 20 is secured to the dash-board 21 of an automobile C. The fixture A is electrically connected 85 by means of conductors 22 with a regulating switch D also mounted adjacently upon the dash-board 21. From this switch suitable connections are made to the battery, magneto, or other source of current 90 supply, of the automobile.

The fixture consists essentially of the socket-sleeve 23, insulating disk 24, cap 25, conductors, holder or collar 26, reflector and guard 27, clamping bands 28 and 29, clamping screws 30 and 31, set screws 32, 32 and 33, and contacts 34 and 35 mounted on the insulating disk 24. In association with these parts of the fixture proper are the conductors 22, which pass through the cap 25 and connect with the contacts 34 and 35 which are adapted to connect to the terminals of the lamp 36 when seated in the socket sleeve 23. These several parts are shown separated from each other in Fig. 4. 100

The lamp socket is made up by assembling the sleeve 23, insulating disk 24 and cap 25. The sleeve 23 is made up of two portions,

one having a diameter slightly larger than the other. This provides a shoulder 37 against which the contact-carrying disk 24 of fiber, or other suitable insulating material, abuts. The cap 25 fits snugly within the enlarged portion of the sleeve 23 and engages the opposite side of the disk 24 so that the latter is clamped firmly between it and the shoulder 37. Oppositely disposed bayonet slots 38, 38 in the adjacent end of the sleeve 23 coöperate with oppositely disposed screws 32, 32 to make a bayonet-joint connection between the cap and sleeve. When the parts are assembled, the screws 32, 32 10 may be screwed down tight to hold the cap in place. The disk 24 must always occupy a definite position relative to the sleeve 23, because the nub or projection 39 on the inside of the sleeve adjacent to the shoulder 20 37 will allow the disk 24 to be seated only when one of the slots 40 or 41 is in line with the projection. Until this alignment is secured, it is impossible to shove the cap 25 and disk 24 far enough into the sleeve to 25 allow the screws 32, 32 to be seated in the bayonet slots 38, 38. The opposite end of the sleeve 23 is provided with two oppositely disposed bayonet slots 41, which co-operate with oppositely disposed pins 42 on 30 the base of the lamp 36. The lamp itself, which is of well known construction, is provided with a cylindrical base 43 which fits snugly into the sleeve 23. It is also provided with a pair of flat terminal faces 44 35 and 45 at its inner end.

The spring contacts 34 and 35 are each composed of a single strip of metal. These strips are bent up at one end to form terminals 46 and 47, which extend rearward from 40 the insulating disk 24. They then extend along the rear face of the disk 24 and then forward through the slots 40 and 41, respectively, to the front side of the disk 24, where they are bent over and shaped at their 45 ends so as to provide terminal contacts which will register with and yieldingly engage the lamp terminal contacts 44 and 45. Each contact strip is secured to the disk 24 by an eyelet rivet 48, which extends through openings in the strip and disk and is headed up at opposite ends. These eyelets may be internally threaded and suitable binding screws 46^a and 47^a inserted therein (Fig. 50 12). The ends of the conducting wires may 55 then be secured under the heads of these screws instead of being soldered to the clips 46 and 47. Either set of these terminals, 46, 47, or 46^a, 47^a, may be supplied alone, or both may be furnished as shown. When 60 the parts are assembled and the lamp is in position, contacts 34 and 44, on the one hand, and contacts 35 and 45, on the other, are in engagement. The conductors 22 extend through an opening in the cap 25 and have 65 their bared ends connected to the terminals

46 and 47. Preferably also, an insulating sleeve 49 of rubber, or other suitable insulating material, surrounds the conductors 22 and effectively insulates them from the cap 25 of the socket. 70

The lamp holder or collar 26 is composed of a strip of metal bent around the smaller portion of the sleeve 23 so as to form intimate contact with it, and terminating in flanges 50 and 51 adapted for the attachment 75 of the clamping rings 28 and 29. These latter rings are shaped so as to closely embrace the periphery of the casing of the speedometer or other instrument upon which the fixture is to be used. The ends 80 adjacent to the holder 26 are bent up so as to fit against and lie substantially parallel to the flanges 50 and 51. A screw 30 passes through openings in the clamping band 28 and the flanges 50 and 51 into threaded engagement with the end of the band 29. By screwing up this screw 30, the parts may be securely held together, and by unscrewing it they may be loosened so that the lamp holder may be adjusted relative to the face 85 of the speedometer. The opposite ends of the bands 28 and 29 terminate in similar substantially parallel ends, and the screw 53 passes through an opening in one of these into screw-threaded engagement with the other, so as to draw the bands into close engagement with the casing of the instrument upon which they are used. The screw 53 may be of any desired length to suit the size of the speedometer casing. Quite a range in the size of such casings may occur without replacing the clamping bands 28 and 29 by bands of different sizes. This is true because the bands are flexible and by having the screw 53 of sufficient length they can be readily drawn into close fitting engagement with the periphery of the casing.

The guard and reflector 27 is of spherical contour and terminates at one end in a substantially vertical flange 54. This flange is adapted to seat at its lower edge into overhanging embracing lugs 55 extending forward from a coöperating substantially vertical flange 56 at the forward end of the holder or collar 26. The upper end of the flange 54 is provided with a threaded opening into which the set-screw 44 may be screwed. The upper edge of the flange 56 is provided with a coöperating notch into which the shank of the screw 33 will slip as the reflector 27 is set in position. By screwing up the screw 33 tightly, the reflector may be held firmly against removal. The reflector 27 incloses the greater portion of the lamp bulb and reflects its rays downward upon the face of the speedometer. It also protects the lamp against breakage from external causes. The lamp, socket and reflector are so proportioned that the lamp cannot be withdrawn from the socket when

the parts are in assembled position. In order to remove the lamp, it is first necessary to loosen up screw 33 and remove the reflector 27, and then the lamp may be readily withdrawn. This construction reduces the likelihood of disconnection or withdrawal of the lamp by meddlers.

It will be seen that by the use of the clamping bands 28 the lamp and reflector may be slipped along the casing of the speedometer in the direction of its axis, and may also be rotated about the casing to any desired angle or position to locate the lamp and socket in the most convenient and effective position, and that by the use of the pivotal connection at 30 the lamp and shade may be tilted with respect to the speedometer, three adjustments of the lamp and reflector with respect to the speedometer being thus provided. This is an important feature enabling the device to be used advantageously in different locations and with different arrangements.

It will be apparent to those skilled in the art that my invention as a whole and in certain details is capable of use in other connections than those herein disclosed and that the disclosure may be altered and modified considerably without departing from the spirit and scope of the invention, as set forth in the appended claims.

Having thus described my invention, what I claim as new and desire to secure by Letters Patent is—

35 1. In a device of the character described, the combination with a dial indicating instrument, of an electric lamp adjacent to the face of said dial, a lamp socket, suitable electrical connections with said socket, 40 clamping members embracing said instrument, and a holder for said socket pivotally and adjustably secured to said clamping members so that it may be tilted in a plane at substantially right angles to the face of 45 said instrument.

2. A device of the character described, comprising an electric lamp, a lamp socket, a holder consisting of a collar embracing said socket and terminating in opposed

flanges, a reflector for said lamp removably secured to one end of said holder, a pair of clamping bands, means for drawing said opposed flanges together and for securing the ends of said bands thereto with a frictional adjustment in the direction of the plane of 55 said flanges, and means for drawing the other ends of said clamping bands toward each other.

3. A device of the character described, comprising an electric lamp, a lamp socket, 60 a tubular holder embracing said socket and having a flange at one end, a reflector more or less inclosing said lamp and terminating in a coöperating flange, embracing lugs on one of said flanges under which the other 65 flange may be seated, and a set-screw threaded into one of said flanges through an opening in the other to securely hold the flanges together.

4. A device of the character described, 70 comprising an electric lamp, a lamp socket, a holder for said socket and lamp having a flange at one end, overhanging lugs extending upward from the lower edge of said flange, a reflector more or less inclosing said 75 lamp and terminating in a coöperating flange adapted to enter at its lower edge beneath said lugs and to rest thereon, and means for securing said flanges together at their upper edge.

80 5. A device of the class described, comprising an electric lamp, a lamp socket, a holder for said socket and lamp having a substantially vertical flange at one end, a reflector more or less inclosing said lamp 85 and having a coöperating substantially vertical flange, lugs on one of said flanges for engaging the other to support said reflector on said holder, and means for removably securing a non-adjacent portion of the coöperating flanges together.

In witness whereof, I have hereunto subscribed my name in the presence of two witnesses.

WILLIAM W. DEAN.
